(57) CLAIM

The ornamental design for a label holder, as shown and described.

DESCRIPTION

FIG. 1 is a perspective view of the top, front and right side of a label holder showing my new design;

FIG. 2 is a left side elevational view thereof, the right side being a mirror image thereof;

FIG. 3 is a perspective view of the top, rear and right side thereof; and,

FIG. 4 is a perspective view of the rear, bottom and right side edge of a front cover thereof detached from the rear portion thereof.
